Assistant Examiner — Alison M Ofstun

(57) **CLAIM**

We claim the ornamental design for a handle with attachment for body trimmer, as shown and described.

DESCRIPTION

FIG. 1 is a perspective view of a handle with attachment for body trimmer showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines illustrate portions of the handle with attachment for body trimmer that form no part of the claimed design.

1 Claim, 6 Drawing Sheets
